DESIGN FOR A LEG FOR AN ARTICLE OF FURNITURE

Harry Padwa, Brooklyn, N. Y.

Application May 9, 1938, Serial No. 77,069

Term of patent 3½ years

To all whom it may concern:

Be it known that I, Harry Padwa, a citizen of the United States of America, residing in Brooklyn, county of Kings, and State of New York, have invented a new, original, and ornamental Design for a Leg for an Article of Furniture, of which the following is a specification, reference being had to the accompanying drawing, forming part thereof.

Fig. 1 is a perspective view of a leg for an article of furniture showing my new design.

Fig. 2 is a bottom plan view thereof.

Fig. 3 is a sectional view of Fig. 1, taken along line 3—3 thereof.

The two sides of the leg opposite those shown in Fig. 1 are plain.

I claim:

The ornamental design for a leg for an article of furniture, substantially as shown and described.

HARRY PADWA.
